METHOD AND APPARATUS FOR DIRECTING
THE SWITCHING OF RAILWAY CARS AT
YARDS AND TERMINALSLeon M. Gibbs, Birmingham, Ala., assignor to
Teleswitch Corporation, a corporation of Ala-
bama

Application April 28, 1930. Serial No. 448,108

33 Claims. (Cl. 104—26)

My present invention relates to a new and improved method and apparatus for directing the switching of railway cars at switch yards and terminals, and has for its particular object to 5 simplify and perfect the method and apparatus which form the subject matter of Letters Patent of the United States, Nos. 1,741,229 and 1,753,602.

In the Letters Patent aforesaid it was contemplated that the switching would be carried 10 out under the direct control of the yard master by providing in his office a dummy yard, comprising miniature tracks and switches corresponding in arrangement to the tracks and switches in the railway yard or terminal, and a 15 plurality of dummies representative of railway cars, which are moved about the dummy yard to follow the movements of their respective railway cars, each dummy carrying suitable indicia descriptive of its respective car, its contents, destination, etc.

My invention, as illustrated in Patent 1,753,602, contemplated that the miniature apparatus in the yard master's office should be automatic in 15 its functioning so that it would cause the dummies to follow automatically backwards and forwards and from track to track of the dummy yard the movements of their respective railway cars in the main yard, thereby displaying in the dummy yard at all times, by the position of dummies therein, the position and identity of cars 20 in the railway yard. In the operation of such a system I selected the car wheels, i. e., one wheel on each axle which I term a "control" wheel, and which is typical of a "control" element on a railway vehicle, to set in operation the necessary 25 automatic agencies to move the dummies from one to another section of the dummy yard tracks and this necessitated the dummies being equipped with a number of feed elements corresponding 30 with the number of "control" wheels or elements on their respective railway cars.

In connection with the automatic operation of the dummy yard, it has been found necessary to 35 perfect storage yard facilities for the dummies and to this end my present invention contemplates the provision of storage tracks, preferably equal in capacity to the dummy yard, which are preferably arranged to permit an initial automatic set up, on approach tracks that connect the 40 storage and dummy yards and are representative of a part of the approach tracks for the railway yards, of dummy trains corresponding to railway trains entering the main yards. My invention also contemplates the provision of automatic 45 means to bring onto a dummy approach track

a dummy for each railway car or vehicle correspondingly approaching the main yard. In like manner, a train of dummies, which correspond to the cars in a railway train departing from the main yard, will be moved onto and either left 60 upon an approach track to the dummy storage yard for the removal of the car indicating data or returned automatically to the dummy storage yard.

To make feasible the initial set-up of the 65 dummy train so that the dummies therein will have feed elements corresponding in number with the "control" elements of the railway train, where wheels serve as the control element, it being well known that the number of "control" wheels on 70 the railway rolling stock will vary widely, the dummies comprise a plurality of elements which I term "wheel counters", each representative of a "control" wheel, and I provide separate tops suitable for assembly with a group of the desired 75 number of wheel counters corresponding to the "control" wheels of the dummy's respective railway car.

In practice, a railway train entering with 151 80 "control" wheels will feed into the corresponding dummy approach track 151 wheel counters which will follow the train into the dummy yard. As the locomotive cuts loose from the train and goes to the round house it will carry out with it wheel 85 counters corresponding in number with its "control" wheels, leaving in the dummy yard track wheel counters exactly corresponding in number with the "control" wheels on the cars to be switched. Thereupon the dummy tops carrying 90 car identifying data can be assembled on such wheel counters to form therewith complete dummies, each comprising a group of wheel counters corresponding in number with the "control" 95 wheels on its respective railway car. Obviously, most of the tops will be of standard size, i. e., adapted to be assembled with a group of four wheel counters, but special tops are provided for special cars, such as cabooses having two "control" wheels or heavy cars or other rolling stock 100 having six or more "control" wheels. When the dummies have been thus assembled, they will display the data descriptive of their respective railway cars and each will stand in the dummy train in corresponding position to its respective car 105 in the railway train. Thereafter, the automatic switching of the dummies can proceed as described in my patents aforesaid.

My invention further contemplates the provision of separate storage yards for dummy 110 wheel counters and dummy tops and of means

whereby the dummy elements are automatically separated and stored in their respective yards when the cars they have represented leave the main yards.

5 My invention also contemplates the provision of novel step by step feed means adapted to coact with the wheel counters and to advance them one at a time from one to another track section in correspondence with the movement of the "control" wheels of the dummy's respective railroad car over suitable track instruments in passing from one to another section of the main yard tracks.

10 My invention also contemplates utilizing the dummy wheel counter to close through itself a circuit to the feed mechanism which will automatically control the action of its step by step feed past a junction point in a dummy yard track.

15 My invention further contemplates the utilization of friction belts or the like to coact with the dummies or their wheel counters to move them back and forth over a track section, there being movable stops to arrest the counters at, or a suitable distance from, a junction point between track sections, which stops, when withdrawn, permit the wheel counters to move past that stop point.

20 Another feature of my invention resides in adapting the dummies or their wheel counters to rest lightly on belts that serve by friction to move them about the dummy yard, so that they will not have the energy to displace their stops as they engage them, nor will they unduly wear the belts as the latter slide under them while they are held stationary.

25 A further feature contemplates the provision of guides or tracks for the dummies which at belt transfer points are angularly disposed to the line of travel of the belts and thus adapted to shift the dummies laterally from belt to belt where such transfer is required. A further feature is to adapt the belt driving means always to move the belts, operating in the receiving and delivering track sections, in the same direction while transferring dummies.

30 A further feature of my invention is the improved electrical apparatus which, responsive to the passage of "control" wheels or elements from section to section of the main yard, will control and energize the mechanism for moving the dummies so as to advance them or their wheel counters to and past a corresponding junction point between corresponding sections of the dummy yard.

35 My invention also contemplates associating with the control for the dummy stops, feed mechanism, and driving belts, of novel electromagnetic means selectively responsive to the direction of movement of a car "control" element to control the direction of travel of the belts that are in immediate control of the related dummy.

40 Another feature of my present invention is the use of a single motor to drive through suitable clutches the several belts that actuate the dummies or wheel counters, the clutches being automatically controlled to drive the various belts in whatever direction will effect such a movement of dummies as will cause them to follow the movement of their respective railway cars.

45 My invention further comprises various other novel details of construction and arrangements of parts, which are hereinafter more particularly described and illustrated in the accompany-

ing drawings which form a part of this specification, and in which:

50 Fig. 1 is a plan view of a typical multiple track railroad switch yard shown in very simple form.

55 Fig. 2 is a plan view of the corelated miniature dummy switch yard, together with the approach tracks leading therefrom to storage tracks, the dummy wheel counter feed mechanism and stops being fragmentally shown to avoid confusion.

60 Fig. 3 is a view showing the layout of driving belts for operating the dummies movable over the miniature switch yard shown in Fig. 2.

65 Fig. 4 is a view showing the corresponding track section junction points of the main yard and dummy yard, with a suitable arrangement of circuits and electromagnetic means employed in the automatic control of the illustrated section of the dummy yard.

70 Fig. 5 is a view corresponding to Fig. 4 showing the track circuit connections employed in the automatic control of dummies moving between the dummy yard and dummy storage tracks.

75 Fig. 6 is an enlarged detail view of a portion of the dummy yard showing switches and related wheel counter feed mechanism and stops in detail and illustrating in dotted outline the single motor driven clutch control transmission for actuating the dummy driving belts shown.

80 Fig. 7 is a detail view showing corelated rotary switches which respectively record the action of car wheels passing a railway track instrument and corresponding dummy movements.

85 Fig. 8 is a view showing the circuit connections between a track instrument and the rotary switches it controls.

90 Fig. 9 is a sectional view taken on the line IX-IX of Fig. 6, showing the pulleys for three juxtaposed belts and a typical magnetically operated clutch control for a belt drive.

95 Fig. 10 is an enlarged view in side elevation showing an assembled dummy entering the dummy storage yard preparatory to the automatic removal of the dummy top from its base here formed by a group of wheel counters.

100 Fig. 11 is a plan view of Fig. 10.

105 Fig. 12 is a detail view of a main yard track switch and the circuits controlled thereby for correspondingly positioning the related dummy yard switch.

110 Fig. 13 is a cross sectional view taken on the lines XIII-XIII of Fig. 6.

115 Similar references refer to similar elements throughout the drawings.

120 The main switch yard conventionally illustrated in Fig. 1 comprises approach tracks 11 and 12 over which the railway cars pass to the yard tracks 13, 14 and 15 by means of the ladder tracks 16 and 17. This yard is provided with a plurality of similar track instruments indicated by the numerals 18a, 18b, 18c, 18d, 18e, 18f, 18g, 18h, 18i and 18j, which will be later described in detail by reference to Fig. 8, and which are arranged adjacent to the several main yard track switches and at any desired point in the main yard switch tracks or the approach tracks adjacent to the yard.

125 In addition to this I provide similar switch boxes 19, 19a, 19b and 19c arranged adjacent to the main yard track switches which boxes are shown in detail in Fig. 12 and which control circuits which will be later described.

130 It will be understood that the tracks 13, 14 and 15 are employed to conventionally illustrate a multiple track railway switching yard which may comprise any desired number of tracks of any desired car holding capacity.

In Fig. 2, I illustrate the corresponding miniature dummy yard which will be installed in the yard master's office and which comprises the approach tracks 11a and 12a, corresponding to the 5 main yard tracks 11 and 12, and ladder tracks 16a and 17a, corresponding to 16 and 17, and dummy yard tracks 13a, 14a and 14b, and 15a, corresponding to main yard tracks 13, 14 and 15. The dummy yard is provided with track switches 20, 10 21, 22 and 23 corresponding to the switch controlling boxes 19, 19a, 19c and 19b in the main switch yard and controlling the passage of dummies from the ladder tracks to the yard tracks. These switches are shown as typical of a simple 15 means for directing the dummies or dummy wheel counters into the desired one of two intersecting dummy yard tracks in correspondence with the movement of a controlling railway car past a switch in the main yard.

20 The approach tracks 11a and 12a are connected to intermediate storage tracks 11b and 12b which are brought together at a switch 24 where they connect with the entrance track to the dummy storage yard 25 which is fragmentally shown.

25 In the apparatus illustrated in Fig. 2, what I have defined as tracks 13a, 14a, etc., are in reality guides formed by the strips or plates 26 of the dummy yard and the spaced-side edges of these guides are adapted to receive between them the 30 rounded shanks 27 (see Fig. 10) of the dummy wheel counters which are preferably in the form of spools each having an annular flange 28 and 29, the bottom flange 28 being slightly bevelled about its under marginal edge and the top flange 35 having a central socket extending down through the shank to receive a pin 30 carried by the demountable dummy top 31. These wheel counters are free to pass along the guides referred to as tracks responsive to their engagement with a plurality of friction driving belts arranged under the guides as is illustrated more clearly in Fig. 13.

Fig. 3 shows the following arrangement of belts suitable for the miniature dummy yard illustrated in Fig. 2. The belts 113a and 115a underlie 45 tracks 13a and 15a and work between the switches in said respective tracks; belts 114a and 114b underlie the tracks 14a and 14b respectively. A wide belt 121 works opposite that portion of the ladder track 16a opposite switch 21; a wide belt 50 120 occupies the same relation in track 16a to the switch 20. In like manner wide belts 122 and 123 work under ladder track 17a opposite switches 22 and 23, respectively.

In Fig. 6 the belts 113a, 114a, 115a, 122 and 123, relative to the switches 22 and 23, are clearly 55 illustrated and from this view it will be apparent how the angular disposition of the tracks or guides, such as 17a, to the direction of movement of the underlying belts will cause the latter to move the dummies or dummy wheel counters along a track and to shift them laterally from belt to belt. In traversing this ladder track 17a to the right a wheel counter will shift from belt 113a onto belt 123 and then onto belt 122, and finally onto belt 112a, or vice versa if moving in the opposite direction.

Several belts are indicated by the numerals 111a and 112a which belts are arranged and 70 adapted to carry the wheel counters or dummies about the approach tracks 11a and 12a and deliver them into the intermediate storage tracks 11b and 12b; the belts 111b and 112b will deliver the wheel counters to the wide belt 124 at the 75 switch 24, which belt 124 will in turn transfer to

or from the belt 125 carrying the dummies into or out of the storage yard track 25.

The several belts are of the endless type, each having suitable end pulleys which are omitted from the showing in Fig. 2, such pulleys being however illustrated in Fig. 9 where 32 represents a narrow pulley for one of the narrow belts and 33 indicates a wide loose pulley and 33a a wide fast pulley for the wide belts, such as 122 and 123.

Where correlated belts for tracks 111a or 112a, 85 are arranged at right angles to each other, to facilitate the transfer of wheel counters or dummies from one to another, the pulleys of one belt are arranged to underlie the top flight of the adjacent belts, this being indicated in dotted lines, Fig. 3.

Fig. 3. The upper flight of each belt rests on and is supported by the table surface 34. The elements 26 forming the dummy tracks, are shown in the form of plates or bars spaced to form the dummy track guides and supported on filler blocks 35 that rest upon the table surface 34 and form between them guides for the several belts. Such an arrangement is more clearly shown in Fig. 13. The upper flight only of the belts rests upon the supporting surface 34, the lower flights returning below that surface and the journals for the pulley shafts are attached to the underside of the support 34, and the pulleys are disposed under openings 36 provided in the surface 34 opposite each pulley so as to permit the endless belt to be assembled and disposed in the manner described. This arrangement is illustrated more clearly in Fig. 6, where the several openings 36 are shown provided for the several pulleys.

105 Each belt passes around a fast and a loose pulley and in order to simplify the shaft arrangement, loose pulleys in transverse alignment with a fast pulley are mounted on the driving shaft for the latter. This is illustrated in Fig. 9, where the loose pulleys for the belts 115a and 122 are shown mounted upon the shaft 55 for the fast pulley 33a for driving belt 123.

110 I prefer to use a single continuously running motor to drive all the belts and in Fig. 3 I show diagrammatically one arrangement of a transmission suitable to this end. Here the motor 40 drives by belts 41 and 42 the driving shafts 43 and 44 in opposite directions. There are eight additional driving shafts 43a, 43b, 43c and 43d, all driven in the same direction as shaft 43 by the connecting belts or chains shown, and shafts 44a, 44b, 44c and 44d all driven in the same direction as shaft 44 by the connecting belts or chains shown. It will be noted that the shafts 43a and 44a, 43b and 44b, etc., are grouped together in pairs and between each pair is a reversing clutch box 45. Such a box is shown in detail in Fig. 9 and comprises two idle sprockets 46 and 47, each carrying a pin 48 and a grooved hub 49 with which a forked arm 50 of its respective bell crank engages. Each crank 50 carries an armature 51 which coacts with one of two magnets 52 and 53. Fast on the shaft supporting the loose sprockets 46 and 47 is a pin 54 with which one or the other of the reversely driven sprocket pins 48 will engage when shifted by the energization of its respective magnet and thus a driving shaft for a dummy conveyor belt is reversibly driven.

115 As such a drive is alike for each conveyor belt driving shaft, a description of one drive will serve for all similar drives. Referring to Figs. 6 and 9, I show shafts 43 and 44 reversibly driven by the motor 40, and shaft 43 by chain 143 drives sprocket 46, and shaft 44 by chain 144 drives sprocket 47. Whichever of sprockets 46 and 47

is shifted magnetically, it will through pin 54, drive shaft 55 in the desired direction and this shaft is journaled in suitable bearings 56 and 57 and supports the loose pulley 32 for belt 115a and 5 33 for belt 122, and drives the fast pulley 33a for the belt 123.

In like manner through a reversing clutch box 45 shafts 44 and 43c drive shaft 58 carrying the fast driving pulley for belt 122. Through a 10 like reversing clutch, shafts 43a and 44a (see Fig. 3) drive shaft 59, which drives the fast pulleys for the three sections forming conveyor belt 112a, one pulley being fast on shaft 59 and the other two driven through the gearing 15 60, whereby all sections composing the belt 112a will move so as to coact in moving the dummies about the track section 12a. Through a reversing clutch, shafts 43 and 44b drive shaft 60 carrying loose pulleys for the belts 114a and 20 123 and a fast pulley for belt 113a. Likewise, shafts 44b and 43b drive shaft 61 carrying fast pulleys for the belts 114a and 114b; shafts 43b and 44c drive shaft 62 carrying the fast pulley for belt 115a and loose pulleys for belts 121 and 25 114b; shafts 44c and 43c drive shaft 63 carrying the fast pulley for belt 121 and loose pulleys for belts 120 and 113a; shafts 43c and 44d drive shaft 64 carrying the fast pulley for belt 120 and the loose pulley for one section of belt 111a; 30 shafts 44d and 43d drive shaft 65 carrying a fast pulley for the long section of belt 111a and by gearing 60a it drives the fast pulleys for the adjacent sections of belt 111a, and also by chain 66, shaft 65 drives shaft 65a at the other end of 35 the table, which shaft carries the loose pulley for the long section of belt 111a, and by gearing 60b drives the fast pulleys for the adjacent sections of belt 111a; shafts 43 and 44b drive a shaft 67 carrying the fast pulley belt 112b; 44b and 43b drive shaft 68 carrying the fast pulley for belt 111b and idle pulleys for one section of belt 111a and one section of belt 112a; shafts 44c and 43c drive shaft 69 carrying the fast pulley 40 for belt 124 and loose pulleys for belts 111b and 112b; shafts 43c and 44d drive shaft 70 carrying the fast pulley for belt 125 and the loose pulley for belt 124; and shaft 43d through a clutch drives shaft 71 carrying fast pulleys for 45 the two narrow belts 72 which act to lift the dummy tops from the wheel counters as they enter the storage yard, see Figs. 10 and 11.

From the foregoing description it will be apparent that the several shafts 43, 43a, etc., 44, 50 44b, etc., are all constantly turning, and through the magnetic control of their related clutch boxes 45 these shafts will serve to impart the desired direction of movement to the various driving shafts for the dummy moving belts and thus 55 these belts under magnetic control can stand at rest or can be reversibly driven to shift the dummies or wheel counters back and forth and from track to track, and along approach tracks 11a, 11b and 12a, 12b into and out of the storage yard 25. I will later describe the automatic control of the dummy moving belts and of the 60 dummy track switches.

In the operation of my invention, it is necessary to provide means to stop the dummies or 70 wheel counters as they approach a transfer point or switch and also to effect a step by step feed of dummies or dummy wheel counters past a track section junction point in correspondence with the passage of their respective control wheels 75 or elements past a corresponding track section junction point in the main yard.

I have illustrated in my Letters Patent No. 1,753,602, one means for effecting a step-by-step movement of the dummies past a track section junction of the dummy yard, but I have simplified and perfected such feed in my present invention, my object being to maintain the requisite positive control of the feed of the dummy while reducing to a minimum the frictional action of its driving belt while it is under control of a stop or of a feed means.

My improved stop and feed means will be best understood by reference to Fig. 6, where I show associated with the dummy track switch 23 at an intermediate point in the converging tracks 17a and 14a a pair of laterally swinging tapered stops 73 and 73a. Each is mounted on a crank arm 74 fast on a vertical axis suitably journaled in the table in position to clear the adjacent driving belts, and fast on the underside of each axis is an armature 75 or 75a coacting with a magnet 76 or 76a. A spring 77 or 77a normally forces its respective stop into operating position across its respective track and thus in position to arrest an approaching wheel counter. When either of said magnets is energized, its stop is withdrawn from position in the track and the dummy counters are free to pass it. These stops are so positioned that they will hold dummies approaching the switch 23 from the left in the clear and so as not to interfere with the throwing of the switch, and they will also hold dummies back in either of tracks 13a and 14a so as not to interfere with dummies moving out of the other of said tracks to the right towards their intersection.

I show a similarly controlled stop 73b in track 15a opposite the switch 22 and in this view I show two step-by-step feed mechanisms, one above shaft 55 in a vertical plane between belts 123 and 122, and the other in line with shaft 58 in a vertical plane between belts 122 and 112a. In other words, these mechanisms are arranged in line with belt junction points and as all of the mechanisms are alike, the description of the one 105 opposite switch 22 will apply to all.

The particular feed mechanism above referred to comprises a vertical rocker shaft 78 suitably journaled in the table 34 and passing freely through a slot 79 in switch 22 that permits that switch to move freely. On the upper end of this rocker shaft is mounted a crank arm 80 carrying at its free end reversely inclined contact plates 81 and 82 which are insulated from each other and from arm 80. At its lower end shaft 78 carries an armature 84 actuated by a spring 83 in one direction and by a magnet 85 in the opposite direction. The spring tends to hold crank 80 in the position shown and its magnet 85, when energized, will rock it to drive its contacts 81, 82 across the track 17a. On the opposite side of the track from crank 80 is a vertical rocker shaft 86 carrying a spring-pressed armature 87 for magnet 85x, and a crank arm 88 upon which are mounted two contact members 89 and 90 insulated respectively from each other and from arm 88 and together forming a wedge-shaped stop similar to 73 and disposed opposite the V-space between the contacts 81 and 82. The spring normally holds this element in operating position as a stop and when the shank 27 of a dummy wheel counter engages contact 89 or 90, due to the wedging action of such contact element, the counter shank will be forced by it against the opposite guide or plate of track 17a and a circuit 145 will be closed from such plate through the wheel

80

counter shank to contact 89 or 90. One side of the battery or current source is connected by a lead 91, see Fig. 13, to the plate 34 and thence through the several bolts to the bars or plates 26 forming the several dummy track guides.

Assuming that the track circuits to be later described will be set to cause the feed mechanism to pass a dummy from left to right along track 17a past the feed mechanism above described, in such event it being understood that the magnets 85, 85x controlling the arms 80 and 88 are so wired as to be energized and de-energized simultaneously, the operation will be as follows. The shank of the foremost wheel counter will contact with the point 89 and close the circuit through it to the opposite side of the track, which circuit will energize the two magnets 85, 85x and will retract the points 89-90 and advance the points 81-82. The point 82 will assume a position to stop the shank of the counter as it is moved to the right by the belts and when the counter shank strikes 82 it will be forced against the opposite side of the track and a circuit closed which will energize magnet M, de-energize magnet L and the magnets 85, 85x and permit the arms 80 and 88 to resume the full line position shown. The circuits controlling the energizing and de-energizing of the magnets 85, 85x will be described later in connection with the general description of circuits. Such a movement is in reality a magnetically controlled escapement movement which will positively feed a wheel counter shank past the stop 89-90 with each cycle of operation of the escapement arms 80 and 88 and the points 81 and 82 are of such size and so positioned that they will work between the spaced shanks of wheel counters when assembled with a dummy top.

It is important to note that the dummy spool counters are not called upon to actuate the escapement mechanism or any switch controlling it but merely to close a circuit which will energize the magnetic means for operating the escapement feed and in this particular my present invention is an improvement over the step-by-step feed mechanism shown in my Letters Patent No. 1,753,602, wherein the dummy was called upon to actuate the switch which would control its step-by-step feed.

An assembled dummy will be best understood by reference to Figs. 10 and 11 wherein the standard type of dummy comprising a top 31 and four wheel counters is shown. It will of course be understood that the top may be longer or shorter, according to the number of wheel counters it must span in order to provide the dummy with a wheel counter for each "control" wheel of the railway vehicle it represents. As shown in the above figures, four similar wheel counters are grouped together and pins 30 carried by the top 31 are inserted loosely in the sockets of the end counters of the group. This holds all four counters in assembled relation and leaves the top free to be lifted therefrom when engaged by the inclined belts 72, see Fig. 10, which will pull the pins upwardly out of the shank openings in which they fit so loosely that they will not bind by reason of the slight cocking action resulting from the inclined lifting belts engaging the normally horizontally disposed top 31.

When the separation of the top from the wheel counters forming a dummy occurs, the belts supporting the wheel counters will be driven in the

same direction as the belts 72 and the wheel counters will be held down from being lifted from the tracks by the engagement of their flanges 28 under the track guides.

Each dummy top carries a spring plate 31a engaging the underside of a removable tag 31b which carries the way bill or car descriptive data. The spring presses the tag against a lip 31c formed by overturning one end of the top plate 31. The pins 30 depend from hubs 30a, similar to flanges 29 on the wheel counters and having their upper ends reduced and riveted through the plate 31.

The shanks and flanges of the wheel counters are rounded so that they will roll against each other and against the track guides, thus reducing friction to a minimum. The flanges of the wheel counters space the shanks sufficiently for the escapement feed mechanism to work between them in the manner above described.

Assuming that wheel counters have been assembled in a dummy track in number corresponding to the "control" wheels of a train of railway cars, the tops intended to be assembled with such wheel counters can be placed in proper sequence in any suitable carrier and with one movement engaged with the wheel counters since the abutting tops and the abutting counters will permit the top pins to drop freely into the appropriate wheel counter sockets and thus a whole train of dummies can be assembled in one operation and in this manner there can be an immediate check as to whether there are any odd wheel counters left, in which event a mistake has been made and a recheck should be made of the cars in the main yard.

The tracks on which the dummies travel about the dummy yard are continuous tracks and the dummy wheel counters cannot be lifted out except at the point where they are fed initially into the storage yard. By this arrangement the wheel counters cannot be accidentally lifted out or misplaced while in use in the dummy switch yard.

Referring to Fig. 12, I show a main yard switch 119b which, as it is thrown, will rock an arm 92 which carries a contact that will close the circuit from wire 93 to one or the other of wires 94 or 95, according to the position of the switch. This action in the arrangement illustrated controls the corresponding movement of the similarly placed dummy yard track switch, and is the same for the several switch boxes 19, 19a, etc.

The dummy yard track switches are all similar and the description of one will apply to all. Referring to the switch 23, Fig. 6, it is pivoted to move about the vertical axis 96 journalled in top 34 and having an armature 97 fast thereon and engaged on one side by a spring 98 and on the other carrying the armature for the magnet 99. The spring normally holds the switch in full line position shown, but the magnet when energized will shift the switch to open track 14a.

While, for purposes of illustration, a switch in the dummy yard track is the simplest means of directing the dummies into one of two branch tracks, I nevertheless again wish to emphasize the fact that it is merely typical of any suitable means that will cause the wheel counters to follow under direction by their "control" wheels into the desired track, which may be done magnetically or by other equivalent mechanical means.

I have already stated that at suitable points in the main yard tracks I dispose what I call track 150

instruments. As these instruments are all similar the description of one will apply to all.

Referring to Fig. 8, I here show a section of main line track rail 100 and alongside this are disposed two arms 101 and 101a which are adapted to be engaged and displaced by a passing "control" wheel on a railway vehicle. As illustrated, they will be depressed and rocked about their horizontal shafts 102 and 102a, which are journaled in bearings 103 and 103a at opposite ends of a base plate 104. The inner ends of these shafts enter a switch box 105 and coil springs 106 and 106a extend from the switch box in opposite directions to engage the arms to hold them in elevated position. Flexible sleeves 107 and 107a extend from the switch box to the hubs on the arms 101 and 101a. The ends of the shafts entering the switch box carry switch points adapted to close the switches 108 and 108a, respectively.

These switches have one side grounded and the other connected by the leads 109 and 109a respectively to the magnets A and B. The arms 101 and 101a are so disposed relatively that a wheel passing to the right having engaged arm 101 will engage 101a before disengaging 101, causing the relay magnet A to be energized and held energized until after B has been energized. While this accomplishes the same result as the track instrument described in my Letters Patent aforesaid, it has the advantage of substituting electrically operated selective mechanism, that can be placed in a protected position in the yard master's office, for mechanically operated selective mechanism that according to my former invention formed a part of the track equipment and was therefore placed in the main yard tracks where it was exposed to weather and rough usage.

My present form of track instrument is rugged and proof against access of water or snow, since the flexible sleeves 107, 107a are waterproof themselves and will prevent moisture gaining access to the switch box and protect the circuits against accidental closing.

In Patent No. 1,753,602, I described a pair of interconnected rotary switch members which were advanced step-by-step, one in response to the passage of "control" wheels over a track instrument and the other to the corresponding step-by-step feed of a dummy wheel representative element past the corresponding step-by-step feed mechanism in the dummy yard. I have simplified the type of rotary switch to be used in this connection and illustrate the same in Figs. 7 and 8. Here each track instrument controls a pair of magnets C and D which operate similar rotary switches.

Describing one of these switches, its magnet C controls a bell crank armature C' which carries a pawl C² that coacts with the ratchet wheel C³ and feeds it one step for each energization of the magnet. A spring stop dog C⁴ prevents the back movement of the ratchet which, as it moves, advances a contact arm C⁵ over a semi-circular contact series C⁶. The arm is connected to wire C⁷ and the several contacts C⁶ are respectively connected to corresponding contacts of a similar correlated rotary switch shown in Fig. 7 where I show the several contacts C⁶ of the instrument controlled by the magnet C connected respectively to the corresponding contacts E⁶ of the instrument controlled by the magnet E. The armature C' has a lug C⁸ which engages a leaf spring C⁹ that tends to hold it away from its magnet and against an adjustable stop C¹⁰. When moved by the magnet the armature will act to open a

spring contact arm C¹¹, breaking a circuit in which a relay magnet to be later described is interposed. The mechanism controlled by the magnet D will have corresponding parts, and its contacts D⁶ will be connected to a similar rotary switch controlled by the magnet F (Fig. 4).

By reference to Fig. 7 it will be observed with respect to the pair of co-ordinated rotary switches shown, that their respective switch arms are on connected contacts and therefore a circuit through switch arms E⁵ and C⁵ to the relay magnet G will be closed and this magnet will hold the several contacts controlled by it in open position, but whenever the switch arms E⁵ and C⁵ are not on connected contacts the magnet G is de-energized and the several contacts controlled by it spring closed.

Having described in detail the various instrumentalities utilized in carrying out the automatic operation of the dummy yard, I will now describe the magnetic means and their controlling circuits which are utilized, attention being first called to Fig. 4.

This illustrates the group of circuits that are controlled by a switch 119b and the pair of track instruments adjacent thereto in the main yard, such group being typical of other like groups which need not therefore be described. In this view the track instruments 18f and 18g and the switch contact box 19b, as shown in Fig. 1, are the ones illustrated, and I show circuits 109 and 109a connecting corresponding switch terminals in the two track instruments, the former leading to the magnet A and the latter to the magnet E, and thence to the ground or return circuit.

Magnet A when energized will control a series of switches which for convenience will be distinguished by numerals as coefficients which progress in numerical order from the magnet and will therefore be referred to as switch A¹, switch A², etc., but to avoid confusion such distinguishing marks will not be applied to the switches in Figs. 4 and 5 of the drawings as any particular switch referred to can be readily found by locating its control magnet by the letter and counting the switches therefor corresponding to the letter's numerical coefficient. Thus, in Fig. 8, when magnet A is energized switch A¹ next to the magnet is opened and switches A² and A³ are closed. The same applies to the magnets B, H, and I and their respective groups of switches. As the circuits controlled by these several magnets are more clearly shown in Fig. 8, reference will now be made thereto.

It will be understood that all switches are moved by the action of their respective magnet against spring action which will cause the switch, when the magnet is de-energized, to open or close the circuit it respectively controls according to its relative position to the contact with which each switch coacts.

Assuming a car wheel to be traveling to the right on track 100, it will first actuate arm 101, close switch 108 passing current over wire 109 to energize magnet A which will close switch A³ allowing current from any suitable source to flow to switch I¹ which normally stands closed and thence to magnet H which is thereby energized. When the car wheel moves onto and actuates arm 101a, it will close switch 103a, pass current over wire 109a to magnet B which will close switch B³, passing current to the then open switch H¹, which leaves magnet I de-energized, and also passing current through the then closed switch H² on through normally closed switch C¹¹ to

magnet H, which is then energized through switch 108. When switch 108 opens, responsive to the passing of the car wheel off its arm 101, the magnet H will be held energized through the closed switch B³ until switch C¹¹ is opened by the armature C¹, but magnet A will be de-energized; switch A¹ will spring closed allowing current to pass from switch B² via H³ and A¹ to magnet C, thereby actuating armature C¹ opening switch C¹¹, de-energizing magnet H, opening switch H³, de-energizing magnet C whereupon the spring retraction of armature C¹ will advance the contact arm C⁵ one step and then release switch C¹¹.

Had the car wheel stopped before releasing arm 101 or had it backed off of 101, then magnet C would never have been energized and therefore only where a "control" wheel passes from contact arm 101 onto arm 101a and releases arm 101 does it cause the contact arm C⁵ to advance one step, and after it has advanced the arm C⁶, if the wheel stops and rolls back to depress arm 101, the action will be the same as if the wheel had approached the track instrument from the right hand side.

When a wheel approaches from the right, it first depresses arm 101a, closes 108a, energizes magnet B, closes switch B³, passes current through switch H¹ and energizes magnet I. After actuating arm 101, switch 108 is closed, energizing magnet A, closing switch A³, and passing current through switches I² and D¹¹ to magnet I, and as soon as arm 101a is released, magnet B is de-energized but magnet I is held energized through switch D¹¹ and current flows through closed switch A² through I³, B¹ to magnet D which actuates its armature D¹, open switch D¹¹, de-energizes magnet I, opens switch I³, de-energizes magnet D and permits its spring retracted armature to advance contact arm D⁵ one step. After the west-bound car has depressed arm 101a and then depressed arm 101 and finally released arm 101a, it is immaterial whether it stops or passes on because the track instrument has then completed the register of a passing wheel and contact arm D⁵ has been advanced one step. On reverse movement after arm 101 has been depressed and then arm 101a has been depressed and finally arm 101 has been released then the reverse passage of a wheel has been registered, the magnet arm C⁵ has been advanced one step, and it is immaterial whether it would remain on 101a or passes on. The essential point is that for a wheel to register both arms of the track instrument must be depressed and the one first depressed must be released to complete the actuation of a registering instrument C or D which will be selectively actuated according to the direction of travel of the controlling wheel. Thus as "control" wheels pass back and forth over track instrument 18b they will selectively advance contact arms C⁵ or D⁵, according to direction of travel of the wheel passing over the instrument.

By having switch C¹¹ hold the circuit that energizes the magnet C closed until the latter's armature has moved the full stroke necessary to actuate contact arm C⁵, I insure the fastest possible reliable operation for such contact arm, as the circuit to magnet C can thus be broken at the instant it has accomplished the function for which it was energized.

Each rotary switch arm C⁵, D⁵ etc., controlled by a yard track instrument, such as 18b to 18h inclusive (Fig. 1), has associated with it a similar rotary switch, such as shown at E⁵ in Fig. 7, and

I will now describe the manner in which a switch such as E⁵ responds to the escapement controlled feed of dummy wheel counters past the junction point in the dummy yard track which it controls.

Referring to Figs. 4 and 7, I show magnets C and E controlling one pair of associated rotary switches and magnets D and F controlling another pair, one pair responding selectively to "control" wheel travel in one direction and the other pair to a reverse direction of "control" wheel travel. As before stated, the corresponding contacts of a pair of switches (C⁶, E⁶ of Fig. 7) are electrically connected, hence when the switching arms C⁵, E⁵ stand on corresponding contacts they are electrically connected, and magnet G is energized. This magnet controls a group of wire switches which will be referred to as G¹, G², etc., the coefficient designating the relative position of the switch counting away from the magnet, as seen in Fig. 7.

In like manner the switch arms D⁵, F⁵ will control the energization of a magnet J similar to G and controlling nine correspondingly designated switches J¹, J² etc. The switches G¹, G², etc., J¹, J², etc., are all spring-pressed to closed position but are normally held open by the energization of their respective magnet G or J. When a "control" wheel passing to the right, actuates track instrument 18f, the rotary switch arm C⁵ will be advanced one contact from the position shown in Fig. 7, thus breaking the connection to arm E⁵, de-energizing magnet G, allowing the closing of the switches G¹ to G⁹ under its control with the following results.

Switch G¹ will allow current to flow through closed switch K¹, controlled by the then de-energized magnet K, to clutch magnet 53a (Fig. 4), which operates belt 113a driving it to the right; switch G² allows current to flow to clutch magnet 53 to drive belt 123 to the right; switch G³ allows current to flow directly to clutch magnet 53b for driving belt 122 to the right; switch G⁴ allows current to flow through then closed switch K² to magnet 76 (Fig. 6) to retract stop 73, thereby permitting dummy wheel counters to move with the belts described past the stop 73 and into engagement with escapement contact 89; switch G⁵ connects magnet L in a circuit leading to contact 89 and open at that point until closed by a wheel counter assuming position between contact 89 and the track and, when so closed, this circuit energizes magnet L, closes switch L¹ and thus completes a circuit to energize magnet E through switch G⁷. When switch L² closes it allows current to flow direct to the magnets 85, 85x, operating the escapement contact and feed elements 81, 82, 89, 90 to let the passing wheel counter move into engagement with contact 82, closing a circuit from the track through 82 to switch G⁶ thence to energize magnet M. When switch L³ closes, a circuit is completed through switch M¹ to hold magnet L energized until magnet M is energized as aforesaid and switch M¹ opened. The functions of G⁸ and G⁹, and also of J⁸ and J⁹ will be described later.

When magnet L is de-energized, it opens switch L¹, breaks the circuit above described to magnet E and allows the latter's armature E¹, responsive to spring retraction, to advance contact arm E⁵ one step and bring it again into circuit with arm C⁵ and again energize magnet G to open the switches it controls, thereby stopping the belt drives described, and resetting the stop 73.

Switch L² being opened, de-energizes magnets

85, 85x and retracts the escapement elements 81, 82, 89, 90 to the position shown in Fig. 4. As these escapement elements thus move back and forth in one cycle, they permit the feed past them of one dummy wheel counter. The cycle of escapement and stop operation above described occurs for the feed past such escapement of each wheel counter and the feed operations will continue as long as the arm C⁵ is ahead of E⁵ by the action of the appropriate track instrument by a passing "control" wheel.

It may happen that C⁵ will be advanced ahead of E⁵ and the actuation of E⁵ to catch up will have to be deferred because E⁵ cannot be advanced until the belts are running in the direction to bring the wheel counters into contact with contact 89, but when this occurs the apparatus will start advancing E⁵ until it catches up with C⁵.

20 When the "control" wheel approaches the track instrument 18^j of Fig. 4 from the right and presses it, arm D⁵ is advanced one step instead of arm C⁵, magnet J is de-energized in place of magnet G in the operation above described, magnets 52, 52a and 52b are energized in place of 53, 53a and 53b, thereby reversing the drive of belts 113a, 122 and 123; circuits are completed to 81 instead of 82 and to 90 instead of 89; switch K³ takes the action of switch K¹; and rotary switch 30 F⁵ takes the place of E⁵.

35 The inter-relation of the parts controlled by the railway track switch 19b (Figs. 4 and 12), will now be described. The switch is set to connect 93 to 94, passing current to magnet N to open switch N¹ and close switch N². Before the track switch was thrown, the circuit was from 93 to 95 and the magnet O. During the throw of the track switch both circuits 94 and 95 are temporarily open, de-energizing both magnets N and 40 O and permitting switches N¹ and O¹ to stand momentarily closed, which passes current to magnet P with the following results.

45 Switch P⁹ closes and current flows from the then closed switch Q¹, controlled by a quick-to-pull-up-and-slow-to-release magnet Q, to the magnet P to hold it energized until magnet Q is de-energized as follows. The opening of switch P¹ breaks the circuit to magnet R, which is slow-to-release like magnet Q, hence switches Q¹ and 50 R¹ will be slow in opening one after the other so that magnet P is held energized long enough (regardless of a quick throw of the track switch) to insure the following operations responsive to the opening or closing of the switches it controls. 55 Assuming the track switch is thrown and magnet N has closed switch N², current will flow from N² to switch P² which stands open until P is de-energized, whereupon current will flow to magnet S and open switch S¹, de-energizing magnet K and opening switch K³ which de-energizes magnet 60 99, permitting spring 98 to throw dummy switch 23 (Fig. 6) to the position shown which corresponds to the position of the track switch controlling 19b (Figs. 4 and 12).

65 Switch P⁴, when closed by the energization of magnet P, passes current to clutch magnet 52a which drives belt 113a to the left, likewise the closing of switches P⁵ and P⁶ will energize the clutch magnets 52 and 52c respectively, driving the belts 123 and 114a to the left; the closing of switch P⁷ energizes magnet 76 to retract stop 73 in track 13a, and switch P⁸ likewise controls the magnet 76a for the stop 73a in track 14a. Thus while P is energized during and shortly after the throw of the main yard switch at 19b, the stops

73 and 73a will be retracted and the belts will have time to move any wheel counters that may be on belt 123 to the left of the stops 73, 73a, thus keeping them in the clear at this switch 23.

Switches K¹ and K⁴ are connected to switch G¹ on one side and on the other side are connected respectively to the clutch magnets 53a and 53c controlling the belts underlying tracks 13a and 14a respectively. Likewise, switches K³ and K⁶ are connected on one side to switch J¹ and on the other side respectively to magnets 52a and 52c for moving said belts reversely to 53a and 53c. Likewise, K² and K⁵ are connected on one side to a common lead to G⁴ and J⁴ and on the other side are respectively connected to stop magnets 76 and 76a.

90 It follows that as magnet K is energized or de-energized it will place magnet G or J selectively in control of the belts and stops for tracks 13a, 14a, magnet K being energized or de-energized according to the position of the track switch 119b.

95 Switch K⁷, when closed by its magnet K, allows current to pass through switch S¹ to magnet K and holds it energized until magnet S is energized and opens switch S¹. When the magnet K is energized, it energizes switch throw magnet 99 via K⁸, responsive to the throw of the switch 119b. To prevent the too quick throw of the switch 23 before the belts, responsive to the control of magnet P, have moved the dummy 100 wheel counters to clear said switch, I interpose switches P² and P³ in the circuits to magnets K and S which control the action of magnet K and it follows that while magnet P is energized the circuits through switches N², P² and O², P³ are 105 held open and thus the throw of the switch point 23 cannot occur while magnet P holds the circuits closed that will cause the belts to move the wheel counters to a cleared position.

110 When switch N² is closed, switch O² is open, 115 and vice-versa, and thus one or the other will pass current through switch P² or P³ to magnet S or K, and when K is once energized it remains energized until S is energized. Hence, if the track switch 119b is reversed, current will flow 120 over 95 to magnet O, which closes switch O² which is connected to the then open switch P³ which, when closed, will energize magnet K. Thus, magnet P will suspend the closing of the 125 circuits to throw dummy switch 23 until de-energized, which cannot occur until the requisite belt movement has taken place to move the dummies to clear switch 23.

130 In Fig. 5 I show the circuits that respond to the track instruments in the approach tracks 130 for the main switch yard, which control the passage of dummy wheel counters across the intermediate storage tracks 11b and 12b from the dummy storage yard 25 into the approach 135 tracks 11a, 12a, or from the said approach tracks into the intermediate tracks 11b, 12b, it being noted that wheel counters are preferably not moved automatically from tracks 11b, 12b into storage track 25 but are shipped therefrom by throwing switch 201 that controls magnet J and 140 the circuits therefrom that will be later described.

145 I show the system of circuits leading from the track instrument 18^j to magnets C and D which are the same as those shown in Figs. 4 and 8 and are correspondingly numbered. As a control wheel passes 18^j to the left it will, through the circuits already described in connection with said Figs. 4 and 8, advance rotary switch D⁵ one step, breaking the circuit to magnet U from corelated rotary switch arm F⁵ which allows switch U¹ to 150

close the circuit through the then closed switch V², controlled by magnet V, to magnet W, closing its switches of which switch W¹ closes a circuit to clutch magnet 53d controlling belt 125; W² 5 delivers current to clutch magnet 53e for belt 124; switch W³ passes current to the magnet 76c for stop 73c; switches W⁴, W⁵ and W⁶ control the escapement feed action at dummy track switch 24 as follows:

10 Switch W⁴ closes the circuit from the track across a wheel counter and escapement feed contact 89a through W⁴ to magnet LL which holds itself energized through closed switch LL⁴; LL¹ when closed delivers current through W⁶ to magnet F; LL³ delivers current to magnets 85a to operate the escapement contacts and feed the wheel counter into position to close a circuit contact 82a and switch W⁵ to magnet MM to break the circuit holding LL energized, and open 15 its switch LL¹ to de-energize magnet F and permit its contact arm F⁵ to advance one step.

As switch LL³ opens it breaks the circuit to magnets 85a permitting retraction of the escapement feed elements. As arm F⁵ advances a step, 20 it breaks a circuit through the rotary switch arm EE⁵ to the magnet X permitting its several switches to close, X¹ passing current through V¹ to magnet Y to close its switches, of which Y¹ controls drive of belt 124 to the right, Y² retracts 25 stop 73c, Y³ drives belt 112b to the right, and Y⁴, Y⁵, Y⁶ and Y⁷ control the escapement feed from track 12b to 30 12a through the switches controlled by magnets AL and AM, and as each wheel counter passes such escapement feed through circuits similar 35 to those already described the dummy controlled rotary switch arm EE⁵, E⁵, and C⁵ will be advanced together one step which, assuming rotary switch arm F⁵ has only advanced one step, will 40 restore the circuit from F⁵ to EE⁵ and thence to the magnet X.

Note, that magnets EE and E are in circuit and hence EE⁵ and E⁵ always move together. 45 Also by causing C⁵ to move with E⁵ responsive to the above described dummy movement, the circuit between these arms will not be broken.

Now one dummy wheel counter will have been 50 passed from track 25 across track 12b onto track 12a, responsive to the passing of one "control" wheel to the left across track instrument 18j.

To effect a wheel counter movement from track 12a to 12b responsive to a "control" wheel passing track instrument 18j to the right, that instrument will, as described in connection with 55 Figs. 4 and 8, cause arm C⁵ to advance one step, breaking the circuit through E⁵ to a magnet Z, and closing its several switches which control circuits similar to those controlled by magnet J (Fig. 4), and will reverse the travel of belts 112a, 112b and will actuate the escapement feed between said belts one complete cycle to feed one 60 wheel counter from track 12a to track 12b, thereby placing said counter in what I term an intermediate storage track. Should it be desired to dispense with the intermediate storage tracks, the belt 112a would then deliver to belt 124 under control of the escapement operated by magnets 85b at switch 24, instead of the escapement at the 65 point of transfer between belts 112a and 112b, and in such an arrangement I would have an automatic return of dummies direct to the storage yard. As the dummy wheel counter is fed past the last mentioned escapement, a circuit to magnet AL is closed and then opened, causing arms E⁵ and EE⁵ to be advanced one step and restor-

ing the circuit C⁵ to E⁵ and opening circuit EE⁵ to F⁵ to de-energize magnet X and energizing magnet Z. Before Z opens its switches Z¹ passes current to magnet AZ which is a slow-to-release magnet and will hold a circuit closed through AZ¹ to magnet V long enough, after the opening of switch Z¹, to allow magnet V to hold itself energized through a circuit from switch V⁴ through switch X², magnet X being de-energized and its switches closed as magnet Z is energized and its switches opened.

Magnet X is de-energized as long as any wheel counter stands in track 12b. If the counters have entered track 12b from track 12a magnet X will have been de-energized by the advance of arm EE⁵ to break circuit F⁵ to EE⁵. If the counters have entered track 12b from track 25, the magnet X will have been de-energized by the advance of arm F⁵ breaking the circuit F⁵ to EE⁵ to magnet X. When X is de-energized by the step-up of arm EE⁵, magnet V will be held energized while X is de-energized. When X is de-energized by the step-up of arm F⁵, magnet V will remain de-energized. As a result of this arrangement, so long as any wheel counters remain in track 12b that have moved thereinto from 12a, magnet V will be held energized and will cause the counters required to be fed into track 12a to be taken from those standing in track 12b until such supply is exhausted which will de-energize magnet X and cause further counters to be drawn from track 25 across track 12b.

When V is de-energized, the passage of wheels over 18j toward the yard will give the action already described, stepping up D⁵ for the wheel F⁵ as a wheel counter passes from track 25 to 12b, and stepping up EE⁵, E⁵ and C⁵ as the wheel counter passes from track 12b into 12a.

When V is energized, the responses will be:— 115 D⁵ will be stepped up by the wheel breaking the circuit through E⁵ to U, closing switch U¹ and passing current through the then closed switch V³ to magnet Y which will control movement of wheel counters from 12b to 12a and step up F⁵ as each counter passes from 12b into 12a and arms EE⁵, E⁵ and C⁵ will stand.

When it is desired to shift dummies or counters from track 12b into storage track 25, switch 201 is closed, energizing magnet T and closing its several switches which will cause the feed of counters on belts 112b, 124 and 125 past stop 73c and the escapement opposite switch 24, and will advance arms D⁵ and F⁵ in unison as each counter enters track 25, thus preventing the breaking of the circuit D⁵ to F⁵ to magnet U, as dummy counters enter storage.

Switch T⁹ closes a circuit to clutch magnet 52f which operates belt 72 (Fig. 10) that travels up 125 an inclined track 272 to a level high enough to detach pins 30 of the dummy tops from engagement with the wheel counters and to store the dummy tops. As all rotary switch arms move they overlap adjacent contacts before passing from one to another (see Fig. 8).

In Fig. 4 the magnets G and J under selective energization responsive to direction of movement of a "control" wheel, constitute the master control relays which drive the belts shown in opposite directions and hence must not be operative at the same time. When the switches controlled by J are closed, those controlled by G should be held open, therefore switch J⁸ is used to pass current to the magnet G to hold it energized regardless of whether the circuit to G from switch C⁵

is closed or open. Magnet AG is held energized by switch J⁹ and this magnet AG corresponds to magnet G in association with the circuits controlled by the adjacent track instruments 18^h and 18ⁱ on the right of the instrument 18^g shown. In like manner switch G⁸ and G⁹ control similar circuits to magnets J and BJ for the same purposes.

Likewise in Fig. 5, switches Z⁷ and Z⁸ control magnets Y and AJ, which latter has corresponding associations with those of the magnet AG above described. Likewise switch Y⁹ controls magnet Z. Any belt is controlled as to direction by magnets such as G and J, Fig. 4, and such opposed control magnets will prevent opposing drives seeking to act on the same belt at the same time.

In this specification, the term "dummy" is meant to apply to any representation movable on or relative to the miniature tracks responsive to the movement of a railway vehicle in the railway switch yard, whether having associated therewith a top adapted to display identifying data or not.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art as are specifically set forth in the appended claims.

What I claim is:—

1. The method of indicating the position and movement of railway cars in switching yards, which consists in causing individual wheel counters to move about tracks in a dummy yard corresponding in track arrangement with the car switching yard, grouping said counters, and associating with each group identifying data relating to a particular railway car in said yard.

2. The method of indicating by remote control the position and movement of railway cars in a main yard, which consists in providing a dummy yard, causing individual wheel counters to follow automatically about a dummy yard the movements of their respective "control" car wheels about the main yard, providing dummy tops each carrying data descriptive of a particular railway car, and assembling each top on a group of wheel counters equal in number to the "control" wheels of its respective car.

3. The method of indicating at a remote point the identity, location and movement of individual railway vehicles in a multiple track switch yard, which consists in providing a miniature yard corresponding in track arrangement to the switch yard, providing in the miniature yard a plurality of counters for indicating the wheels of railway vehicles in the switch yard, causing said counters to follow in the miniature yard the movement of the railway vehicle wheels in the switch yard, grouping said counters according to the grouping of wheels on each of said vehicles, and assembling with said groups in the miniature yard data to identify the corresponding vehicles.

4. The method of indicating by remote control the position and movement of railway cars in a main yard through the employment of a dummy yard having a track arrangement similar to that of a railway switching yard, which consists in causing dummies to move about the dummy yard tracks following their respective railway cars about the railway yard tracks, and causing the

dummies to move automatically from storage tracks into the dummy yard as the railway cars they are to represent respectively enter the railway yard.

5. The herein described method of indicating the position and movement of railway cars in switching yards, which consists in providing wheel counters, each representative of a railway car wheel, providing a dummy switch yard and a dummy storage yard, causing wheel counters to move from said storage yard into said dummy switch yard responsive to the entry of railway car wheels into the related main switch yard, and causing said wheel counters to move about the dummy yard following their respective car wheels.

6. The herein described method of indicating the position and movement of railway cars in switching yards, which consists in providing dummies, providing a dummy switch yard, a dummy storage yard, and an intermediate storage track between the said yards, and causing dummies to move into said dummy switch yard from said intermediate storage track until the supply in the intermediate storage track is exhausted before causing dummies to move from said dummy storage yard into the dummy switch yard.

7. The herein described method of operating a railway switch yard, which consists in providing a dummy yard corresponding to the switch yard, providing dummies in the dummy yard corresponding in location and identity to individual cars in the switch yard, providing a dummy storage yard and dummies therein, providing an intermediate storage track between the dummy yard and the dummy storage yard, causing dummies to move into the intermediate storage track from the dummy yard responsive to cars leaving the switch yard, causing dummies to move into said dummy yard from said intermediate storage track until the supply in said track is exhausted, and causing dummies to move from the dummy storage yard through the intermediate storage track to the dummy yard responsive to the entering of cars into the switch yard when the said supply in the intermediate storage track is exhausted.

8. In an apparatus of the character described, a dummy yard having tracks and switches representative of the tracks and switches of a main yard, a dummy storage yard, and means to collect dummies, representative of a train of cars leaving said main yard, adjacent to said storage yard ready to be shifted into said storage yard.

9. In an apparatus of the character described, a miniature dummy yard having a trackage and switch arrangement similar to that of a main yard, approach tracks leading into the dummy yard representative of tracks in the main yard, and a storage track with which said approach tracks connect, and automatic means to move dummies from the storage track into appropriate approach tracks responsive to the approach of railway cars to the main yard.

10. In an apparatus of the character described, a miniature dummy yard having track and switch arrangement corresponding to a main yard, dummies, means to cause the dummies to move automatically about the dummy yard responsive to the movement of their respective railway cars about the main yard, an approach track for the dummy yard, an intermediate storage track into which said approach track leads, and a storage track with which said intermediate storage track connects.

11. In an apparatus according to claim 10, automatic means to bring dummies out of the storage yard across the intermediate storage track and into the approach track, and automatic means to bring dummies from the approach track into the intermediate storage track. 80
12. In an apparatus of the character described, a dummy yard having tracks and switches representative of a main yard, a dummy storage yard, wheel counters in the storage yard each adapted to represent a control wheel on a railway vehicle, approach tracks leading into the main yard, corresponding approach tracks leading into the dummy yard and connected to the storage yard, and means responsive to entry of vehicles into the main yard to effect movement of wheel counters into the dummy yard. 85
13. In an apparatus of the character described, a dummy yard having tracks and switches representative of a main yard, a dummy storage yard, wheel counters in the storage yard each adapted to represent a control wheel on a railway vehicle, approach tracks leading into the main yard, corresponding approach tracks leading into the dummy yard and connected to the storage yard, means responsive to entry of vehicles into the main yard to effect movement of wheel counters into the dummy yard, and separable tops adapted to be assembled with groups of wheel counters in the dummy yard for representing vehicles in the main yard. 90
14. In an apparatus of the character described, a dummy yard having tracks and switches representative of a main yard, a dummy storage yard, wheel counters in the storage yard each adapted to represent a "control" wheel on a railway vehicle, approach tracks leading into the main yard, corresponding approach tracks leading into the dummy yard and connected to the storage yard, and means responsive to the passage into the main yard of a "control" wheel on a railway vehicle, to move a wheel counter from the storage yard into said dummy yard. 100
15. In an apparatus of the character described, a miniature dummy yard having track and switch arrangement corresponding to a main yard, dummies, means to cause the dummies to move automatically about the dummy yard responsive to the movement of their respective railway cars about the main yard, approach tracks for the dummy yard, intermediate storage tracks into which said approach tracks lead, a storage track with which said intermediate storage tracks connect, automatic means to bring dummies out of the storage track across the intermediate storage tracks and into the approach tracks, automatic means to bring dummies from the approach tracks into the intermediate storage tracks, and a manually controlled means for shifting dummies from the intermediate storage tracks into the storage track. 110
16. In an apparatus of the character described, a miniature dummy yard corresponding to a main yard and having approach tracks leading to and connecting with a storage track, dummies movable about said dummy yard and comprising separable tops, means to force the dummies into the storage track, and means to automatically disengage the dummy tops from the dummies. 115
17. In an apparatus of the character described, a miniature dummy yard corresponding to a main yard and having approach tracks leading to and connecting with a storage track, dummies movable about said dummy yard and comprising separable tops, means to force the dummies into the storage track, and means to substantially as described. 120
18. In an apparatus of the character described, a dummy yard having tracks representative of those in a main yard, dummies in said dummy yard representative of railway cars in said main yard, a dummy storage yard having dummies therein, a plurality of tracks connecting the dummy yard with said storage yard and representative of the several approach tracks to the main yard, and means responsive to the entry into the main yard of a railway car over any approach track to withdraw a dummy to represent it from said common storage yard, and deliver same into the appropriate dummy yard track. 125
19. In an apparatus of the character described, a miniature yard having a track arrangement corresponding to the main yard, dummies representative of railway cars movable about said miniature yard tracks, endless belts underlying portions of said tracks and adapted to support the dummies in a position to be guided by the tracks, the tracks at said portions being arranged transversely of the belts to effect a lateral transfer of dummies from belt to belt, and automatic means responsive to a railway car's movement, to control the movement of the dummies at transfer points. 130
20. In an apparatus according to claim 19, in which the miniature yard comprises ladder tracks and switches interposed therein, each ladder track being disposed transversely across a plurality of belts and adapted to transfer a dummy from belt to belt as it traverses the ladder track, and said automatic control means being disposed opposite each transfer point in the ladder track. 135
21. In an apparatus of the character described, a miniature yard representative of a main yard, dummies representative of railway cars and adapted to move about said dummy yard, and means automatically responsive to the movement of railway cars in the main yard to control the movement of dummies past a corresponding point in the dummy yard, said means comprising an escapement feed for moving a dummy step-by-step, the escapement being controlled by electric circuits established through the dummy being actuated thereby. 140
22. An apparatus according to claim 21, in which the said escapement feed comprises contacts adapted by engagement with the dummy in feeding it to close said controlling circuit through the dummy to its tracks, and in which the dummy yard tracks are insulated from the contacts. 145
23. In a dummy switch yard having a track arrangement similar to a main railway yard and dummies representative of railway vehicles movable over the dummy yard tracks, means automatically responsive to the movement of a railway vehicle past a given point in the main yard for feeding a dummy past a given point in the dummy yard, said means comprising a magnetically actuated escapement having wedge contact means on one side of the track and spaced complementary wedge contact means on the opposite side of the track, magnetic means to move said contact means crosswise of the track simultaneously, and elements on the dummy adapted to be engaged and actuated by the wedge means, substantially as described. 150
24. In an apparatus of the character described, 155

- a miniature yard, dummies movable thereover, a plurality of actuators for moving the dummies about said yard, a common motor, reversible drive transmissions therefrom to said actuators, and mechanism controlled automatically by the movement of railroad cars in a main yard to control selectively the direction of drive of said transmissions. 80
25. In combination, a miniature yard having a plurality of switch tracks and dummies movable thereover, a motor, a plurality of dummy propellers adapted to be driven by said motor through a transmission comprising a clutch controlled reversible drive for each propeller, and means automatically controlled by the movement of railroad cars in a main switch yard to control selectively said clutch controlled drives. 85
26. In combination, a main switch yard track instrument comprising displaceable switches adapted to be actuated by a passing car successively according to its direction of travel, circuits from said switches, remote electro-magnetic mechanism controlled by said switch circuits and comprising relay magnets and correlated rotary switches, a miniature switch yard similar to the main yard, dummies movable over said miniature switch yard, and actuators for the dummies controlled as to direction and operation by said electro-magnetic mechanism. 90
27. An apparatus according to claim 26, in which the dummy yard track switches are provided with, and controlled by, electro-magnetic means associated with the electro-magnetic mechanism for moving the dummies, in combination with dummy switch control circuits having make-and-break switches operable by a railway car according to the track it takes at a switching point. 100
28. In an apparatus of the character described, a dummy switch yard having tracks, dummies movable along said tracks, switches to direct the dummies, friction drives to advance dummies past a switch, means to stop the dummies in a cleared position relative to said switch, and remote control means to release said stop means and throw said switches selectively. 105
29. In an apparatus of the character described, a dummy switch yard having tracks, dummies movable along said tracks, switches to direct the dummies, friction drives to advance dummies past a switch, means to stop the dummies in a cleared position relative to said switch, remote control means to release said stop means and throw said switches selectively. 110
50. 30. In an apparatus of the character described, a dummy switch yard having tracks, dummies movable along said tracks, switches to direct the dummies, friction drives to advance dummies past a switch, means to stop the dummies in a cleared position relative to said switch, remote control means to release said stop means and throw said switches selectively. 115
55. 31. In an apparatus of the character described, a dummy switch yard having tracks, dummies movable along said tracks, switches to direct the dummies, friction drives to advance dummies past a switch, means to stop the dummies in a cleared position relative to said switch, remote control means to release said stop means and throw said switches selectively. 120
60. 32. In an apparatus of the character described, a dummy switch yard having tracks, dummies movable along said tracks, switches to direct the dummies, friction drives to advance dummies past a switch, means to stop the dummies in a cleared position relative to said switch, remote control means to release said stop means and throw said switches selectively. 125
65. 33. In a system of the character described, a main yard, a dummy switch yard, tracks having switches, dummies movable along said tracks automatically responsive to movements of corresponding cars in the main yard, electro-magnetic means to effect such automatic dummy operation comprising dummy stop means in the dummy tracks adjacent to and opposite each switch, and a reversible drive to move dummies past a switch under control of said stop means, the stop means opposite the switch comprising relatively movable elements which coact with the dummies to feed them step-by-step past it. 130
